UNITED STATES PATENT OFFICE

JAMES N. MACRAE, OF STAMFORD, CONNECTICUT, ASSIGNOR TO PETROLEUM HEAT AND POWER COMPANY, OF NEW YORK, N. Y., A CORPORATION OF DELAWARE

IGNITION MECHANISM FOR OIL BURNERS

Application filed April 10, 1929. Serial No. 353,950.

This invention relates to ignition apparatus particularly designed for use in connection with oil burning installations, and has for one of its objects the provision of 5 an ignition apparatus which is moved into and out of operative position with respect to the fuel to be ignited. In the case of an oil burner installation the apparatus is moved into and out of operative position relatively 10 to the burner nozzle. In this way any damage to the apparatus, due to the heat of the burning fuel, is avoided.

A still further object of the invention is the provision of an ignition apparatus of 15 the general character above referred to in which current is taken direct from a power line, thus avoiding the necessity of a step up transformer such as is necessary in spark gap ignition. The elimination of the 20 former reduces cost, servicing and radio interference.

A still further object of the invention is the provision of an ignition apparatus having the characteristics briefly referred to 25 above which is adapted for use with oils having a flash point as high as 220° F., whereas ignition apparatus now used is adapted for oils having a flash point between 150° F. to 155°, maximum.

30 This, of course, is of material advantage commercially, while the elimination of the necessity of a transformer such as is required with spark gap apparatus and the ability to plug into the power circuit found 35 on the job imparts to my improved construction advantages which are material as compared with existing ignition apparatus for oil burning work.

More specifically the present invention 40 provides ignition apparatus adapted to be reciprocated into and out of firing position, the movement of the apparatus out of firing position being accomplished automatically in that the apparatus is returned to initial 45 position by a spring placed under tension by the movement to operative position of the apparatus. Furthermore, the present invention provides a contact control mechanism whereby the circuit through the heating element of the igniter is closed when the igniter

has reached firing position with respect to the oil burner nozzle. The igniter element relied upon for igniting the fuel is a non-metallic resistance element, resembling in appearance the compound commercially 55 known as silicon carbide, the material known in the trade as "Globar" and purchasable in the open market being exceedingly well adapted for my purpose. Such a heating element provides an extended incandescent 60 area of sufficiently high temperature to effect the desired ignition of fuel oil, the flash point of which may be materially higher than those for which spark gap ignition is adapted.

In the drawings accompanying this application:

Fig. 1 shows more or less diagrammatically installation of my apparatus in connection with an oil burner;

Fig. 2 is a side elevational part sectional 70 view of an embodiment of my invention;

Fig. 3 is a sectional plan view of Fig. 2; and

Fig. 4 is a section on the line 4—4 of Fig. 2.

Referring to the drawings in detail, my 75 apparatus embodies a suitable casing designated 1, so designed as to be bolted or otherwise rigidly secured in the front of a furnace as shown in Fig. 1. In order that the igniter element of the apparatus may be 80 brought into proper position relatively to the burner nozzle 2 as will be presently described, the casting 1 is so designed that the apparatus is set at an angle to the burner as is customary in electrical ignition oil burn- 85 er apparatus.

The housing or casing 1 is provided with a plurality of rods which may be termed guide rods shown at 3 and 4, screwed or otherwise rigidly secured to the housing as 90 shown for example in Fig. 3.

5 designates a tube which may be conveniently flanged as shown at 6 and bored for the reception of the guide rods 3 and 4. This tube is adapted to be reciprocated as will 95 appear hereinafter.

Secured to the front end of the tubular member 5 is an insulating member of a good grade of porcelain designated 7. I have found the material known commercially as 100

sillimanite well suited for this purpose. This insulation or insulating member is secured to the member 5 by screws 8. Secured to the rear end or rear wall of tubular member 5 is a rod 9, which in the present instance constitutes the operating member by which the igniter element is moved into and out of operative position. This rod 9 is operated to the left as viewed in Fig. 3 by a torque motor 10 and a suitable gear train, and is returned to inoperative position by a spring 11. I wish it to be distinctly understood, however, that other mechanism may be employed for effecting reciprocation of the igniter mechanism, the torque motor and gear train having been shown merely for purposes of illustration.

Secured to the rear end of the tubular casting member 5 is a flexible metallic armor tube 12 and through this tube and through the casing 5 I lead the necessary conductors 13 and 14 by which current is conducted to the igniter element.

The conductor 14 is connected to a metal rod 15, nickel chromium alloy for example, which is mounted in the insulating member 7 while the conductor 13 is connected to a post 16 also mounted in the member 7. The insulating member 7 also carries a metal supporting rod 17, nichrome for example, secured thereto in the same fashion as just described in connection with the rod 15 and across the outer ends of these two rods is a flat metal bridge plate 18 which may also be of nickel chromium alloy, this plate being rigid with the rods.

The stud or post 16 to which the conductor 13 is attached also secures a spring arm 19 in place to the insulator 7. This spring arm 40 is cup shaped as shown at 20 at the end remote from its point of attachment to the stud 16 and has secured to it a cup shaped member 21 preferably of aluminum.

Intermediate the aluminum member 21 and the end of the spring contact 20 and the bar 18 at the outer ends of the rods 15 and 17 is igniter element 22, an aluminum plate 23 or other metal being provided between the outer end of this element and bridge plate 18. The tension in spring contact arm 19 holds the igniter element in firm engagement with the cup shaped member 23 so that good contact is obtained at each end of the igniter element.

55 The igniter element 22 as above pointed out is of such a character as to be exceedingly well adapted for my purpose in that the same presents a large or extended incandescent area and is operable on the usual power circuit, 110 volts for example, direct, i. e., without the interposition of a step up transformer, and by reason of its extended surface or area is capable of use with fuel oils having a much higher flash point than 60 the fuel oils which are usable with spark

gaps and such type of igniter apparatus. This apparatus is also quite distinct from ignition apparatus such as sometimes used for gas ignition, in which a filament is employed, such devices or apparatus being entirely unsuited to the uses for which my apparatus is intended.

70 The material which I have found suitable in the construction of the igniter element is known commercially as "Globar" and is the 75 trademark of a product manufactured by the Globar Corporation of Niagara Falls, New York. This product is a nonmetallic resistance element and resembles in appearance the compound known commercially as silicon 80 carbide. It has a working temperature up to 2750° F., its coefficient of expansion is extremely low, being one-half that of iron, while rapid heating or quick cooling has no effect on the structure of the element. Another advantage of this type of element is that the same quickly attains working temperature and will successfully withstand reasonable overloads.

85 I have mentioned above that at each end of the heating element 22 I provide an aluminum plate, these plates being designated 20 and 23. These plates are provided for preventing the formation at each end of the igniter element of a film of non-conducting 95 material, the operation of the element 22 without these plates apparently having some chemical reaction with the bar 18 for instance causing the formation of a film which is a poor conductor of electricity. Aluminum 100 overcomes this drawback effectually, although it is to be understood that other metal may be substituted therefor if desired.

In addition to the foregoing I find it of 105 advantage to provide for the automatic closing of a circuit through the igniter when the igniter has been moved to or approximately to its operative position with respect to the burner tube 2. In this connection I pivot a plate 24 to any convenient part of the apparatus as to a bracket 25 for instance. This plate has a sloping face 26 as shown on Fig. 2 and carries on its upper side a mercury contact tube 27 suitably connected to the conductors 13 and 14 as shown.

110 The location of the plate 24 and the shape of its face 26 is such that when the apparatus is moved to the left as viewed in Fig. 2 the flange 6 will engage the plate and gradually move the same about its pivot to tip the tube 27 and close a circuit through the heating element 22 at the time the igniter apparatus has been advanced to approximately 115 its operative position with respect to the burner tube. Obviously upon movement of the igniter in the opposite direction toward inoperative position the tube 27 will restore itself to its original position and open the circuit of the apparatus.

120 From the foregoing it will be apparent that 130

I have provided ignition apparatus particularly adapted for oil burning apparatus, wherein the igniter element is adapted to be moved into and out of operative position with respect to the fuel or other material to be ignited, the igniter element being of such a type as to present a large extended incandescent area to the material to be ignited, this large area enabling the apparatus to be used with oils having a much higher flash points than oils with which ignition apparatus of the spark gap type are usable.

It will be seen also that my apparatus eliminates the necessity for transformers and the like in its operation, with their attendant difficulties and disadvantages.

It is evident that various modifications may be made in the construction above described within the purview of this invention.

What I claim is:—

1. Ignition mechanism comprising an electrode, means for moving the electrode into and out of operative position, a switch for controlling a circuit to said electrode, a pivoted member mounting said switch, and means carrying said electrode and movable therewith and adapted to engage said pivoted member to close said switch when the electrode is moved toward closed position.

2. Ignition apparatus comprising a fixed housing, a casing therein, means for moving said casing in said housing, an electrode of non-metallic material carried by said casing and movable therewith into and out of operative position, and a switch closed by the movement of said casing to carry the electrode into operative position, for closing a circuit to said electrode.

3. Ignition apparatus comprising a non-metallic resistance element as an electrode, a pair of metal supporting rods, a metal bridge across said rods, metal means intermediate the electrode and said bridge member for preventing the formation of a non-conducting film between the electrode and bridge, a spring contact for pressing the electrode into contact with said intermediate metal means, and metal intermediate the spring contact and electrode for preventing the formation of a non-conducting film between the contact and electrode.

This specification signed this 5 day of April, 1929.

JAMES N. MACRAE.
